BENCH

Warren R. Black and Bror W. Henrikson, Grand Rapids,
Mich., assignors to American Seating Company, Grand Rapids, Mich., a corporation of New Jersey

Filed Aug. 11, 1960, Ser. No. 61,704

Term of patent 14 years

(Cl. D15—11)

The dominant features of the design comprise the longitudinally grooved bench top in combination with the drawers depending therefrom and the downwardly-outwardly extending pairs of supporting legs therefor, all as shown.

We claim:

The ornamental design for a bench, substantially as shown and described.
